UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

MACHINE FOR FINISHING STEREO TYPE PRINTING-PLATES.

1,207,675.

Specification of Letters Patent.

Patented Dec. 5, 1916.

Application filed August 11, 1910. Serial No. 576,723.

To all whom it may concern:

Be it known that I, HENRY A. WISE Wood, a citizen of the United States, residing at New York, in the county of New York and State of New York, have invented a new and useful Machine for Finishing Stereotype Printing-Plates, of which the following is a specification.

This invention relates to a machine for trimming and finishing stereotype printing plates. It is particularly adapted for operation on flat plates.

The principal objects of the invention are to provide simple and efficient means for trimming the four edges of the plates and shaving the backs, and means whereby the plates can be removed directly from a plate supporting device, or otherwise supplied to the machine and moved along the machine past the trimming and shaving devices without changing their direction of motion so that the width of the machine can be reduced to a minimum; to provide simple means for turning the plates after they have been trimmed on two opposite edges so that they can be trimmed on the other two edges by saws or trimming knives, substantially in alignment with those used for trimming the first two edges; to provide simple and efficient means for drawing the plates out of the supporting device through the first trimming cutters and depositing them on the turning table; and simple means for releasing the plates therefrom so that they can be delivered from the turning table by another carrier.

The invention also involves improvements in the arrangements of the shaving device and in the relative arrangement of the shaving device, trimming knives or saws, and carriers, as well as in other details of construction as will appear hereinafter.

Reference is to be had to the accompanying drawings in which—

Figure 1 is a side elevation partially in section along the side of the frame of a machine for finishing flat stereotype plates constructed in accordance with this invention. Fig. 2 is a plan thereof. Fig. 3 is a transverse sectional view on the line A—A of Fig. 1, and Fig. 4 is a view, illustrating a modification of the shaving mechanism.

The invention is shown as used in connec-

tion with plate supports 10—11, one of which is movable toward and from the other and which may constitute the cope and drag of a casting box, and it is preferred to take the stereotype plate from these supports when the movable one is retracted and deliver it to the finishing mechanism. The movable support can be operated in any desired way but it is shown herein as being reciprocated from a cam shaft 12 by link and lever connections 13, cam 14 and cam roller 15. On the shaft 12 also is a cam 16 which operates a cam roller 17 on a spring-pressed lever 18. This lever is provided with a curved segment or rack 19 meshing with a pinion 20 which oscillates a gear 21 meshing with a rack 22. This rack is located on a slide 23 which is movable on a guide 24. It will be obvious that the rotation of the cam 16 will cause the gear segment 19 to oscillate and the slide 23 to reciprocate. Mounted on this slide 23 are arms 25 projecting toward the plate supports. On each of these arms is pivotally mounted a finger 26 having a hook 27 on the end and a spring 28 for holding the finger up. Each finger is provided with a forward projection 29, the purpose of which will be explained hereinafter. It will be obvious that the reciprocation of the slide 23 will move the fingers in and out between the plate supports to pull the plate out, the plate being cast with notches to receive the hooks 27.

As the fingers pull the plate from the supports 10 and 11 over two supporting bars 30 the plate is trimmed on its opposite edges by a pair of trimming saws or knives 31. These are located on a shaft 32 having a pulley 33 thereon which is operated from the main shaft 12 in any desired way, preferably so as constantly to rotate. When the fingers pull the plate across the supporting bars 30 they deposit it on a table 34. They move forward until the plate comes up against stops 35 on this table. At that time another operation takes place, due to the motion of a cam 36 on the shaft 12. This cam operates a roller 37 on a rod 38 which is connected by links and levers or the like with a slide 39. This slide is guided in vertical guide ways 40 fixed to the frame of the machine. Carried on ways 49 on the slide 39 is a block 41 supporting a rod 42

over which the tails or projections 29 come. The rise of this rod thus raises these projections and depresses the hooks 27 out of contact with the plate. The slide 23 continues 5 to advance however, and the rod 42 later is engaged by the projections 29, this motion being opposed yieldingly by springs 43. It will be observed that the slide 39 has no horizontal motion but it serves as a 10 support for the block 41 and permits the latter to move forward with the slide 23. When the slide 23 moves back, the springs 43 pull the block 41 back until the rod is substantially in the center of the slide 39. 15 The guides 40 have projections 44 for limiting the rearward motion of the block and leaving it in position to operate the fingers on the next rearward motion thereof. While the slide 23 and the connected parts 20 are moving back through this idle motion another operation takes place as follows:— A cam 50 on the shaft 12 operates a cam roller 51 on a sliding rod 52. This rod is provided with a rack 53 which slides in 25 guides 54 on the frame. This rack meshes with a gear or segment 55 connected with the table 34. Consequently, as the rack reciprocates, the table turns. The parts are so designed as to cause the table to turn at 30 this time through a quarter revolution so as to bring one of the trimmed edges to the front, with respect to the direction of travel of the plate and the other to the rear. The table 34 is swiveled in a stand 56 to permit 35 this turning operation, and it is turned positively in both directions by the movement of the rack. It brings a plate around to the position just specified and after the plate is removed, the table returns to its 40 normal position ready to receive another plate. It will be understood, of course, that when the table moves around a quarter turn, it brings the stops 35 out of the way so that 45 they merely act as side guides for one edge of the plate. At this time a finger 59 is operated by a cam 60 on the shaft 12 which engages a cam roll 61 on a bell-crank lever 62 which carries a segment 63 meshing with a pinion 64. This pinion rotates a gear 65 which reciprocates a rack 66 fixed 50 to a slide 67. This finger will not be described herein in detail, as it is substantially the same as the corresponding finger shown and described in my prior Patent No. 55 1,164,607, filed January 12, 1910, and patented December 14, 1915, and in a divisional application, Serial No. 48,985, filed September 4, 1915. This finger, however, takes the plate from the table 34 across a slotted support 68 and delivers it to a shaver table 69, with its front side against a stop 70. While 60 on this table the plate can be shaved in any desired way. In the first three figures the shaving is shown as accomplished by means 65 of a transversely reciprocating shaver 71.

This is reciprocated in the present case through shafts 72 and 73, the latter of which has a crank 74 provided with a roll 75 working in a track 76 on a sliding head 77, carrying the shaver 71.

The head 77 carries sets of brackets 80 and 81 on the first of which is journaled a shaft 82 carrying the rotary shaver 71 and on the other of which is journaled an idler 84. The distance between the shaft 82 and idler 84 is greater than the traverse of the slide or head 77. Mounted in a stationary position on the frame is a bracket 85 carrying idlers 86. The shaft 82 is driven from a driving pulley 89 by a belt 87 passing over the idlers and over a pulley 88 on the shaft 82. It will be obvious that as the head 77 reciprocates, the belt will be paid out on one side of the idlers 86 as much as it is drawn on the other so that the rotary shaver will be operated in all positions of the head 77. It will be obvious that with this construction the shaver will travel back and forth rotating all the time and it is so timed as to shave the back of the plate while resting on this table. After this, another finger 90 which moves with the slide 67 engages the plate in a manner described in my above mentioned patent and application. This delivers the plate first on a support 91 and then in the same direction on any desired kind of a conveyer, a simple endless belt construction 92 being illustrated herein. While moving along the support 91 the plate preferably is trimmed on two edges by 102 trimming knives or saws 93. These are substantially in line with the first trimming saws 31 and are constantly operated in the same way; when the plates are cast with sufficient accuracy either or both sets of saws can be omitted, or the machine can be used only for trimming, the shaver being omitted.

In Fig. 4 a simple form of shaver is shown consisting merely of a blade 99 110 mounted on the slide 77.

The sequence of operations is as follows: After the cast plate is made or located in the plate supports 10 and 11, the cam 14 operates the link 13 and draws the support 11 down away from the plate leaving it supported by the member 10, then the cam 16 operates the lever 18 and the slide 23 which projects the fingers 27 into the position shown in Fig. 1. The continued operation of this cam then draws the slide back together with the fingers 27 which have engaged the plate and which draw the plate horizontally on the supporting bars. Its edges are trimmed by the saws 31 and it is then deposited by a continuous motion of the hooks 27 on the table 34 and is brought up against the fixed stop 35 thereof. Just at this time the projections 29 come over the block 41 and that is raised by the opera- 130

tion of the cam 36, link 38, and slide 39. The effect of this is to lower the hooks 27 out of engagement with the plate and release the plate from these hooks. As the arms 25 5 continue to move in the same direction the block 41 and shaft 42 move with them so as to allow the hooks absolutely to clear the plate. Then the cam 50 operates the rack 53 and turns the table a quarter way around. 10 The cam 60 then comes into operation to move the finger 59 into a position to engage the plate and draw it farther along in the same direction, but of course with another edge forward. This carries the plate across 15 the supports 68 to the shaver table 69 against the stop 70. The shaver 71 then operates transversely to shave the plate. Then the finger 90 engages the plate and delivers it on its support 91 and from that on a 20 conveyor 92. While moving along the support 91 it is preferably trimmed by the trimming knives or saws 93. It will be noted that although the plate turns around 90° during these operations the motion of the plate is 25 continuously in a straight line from the supports 10 and 11 to the conveyor 92.

It will be noted that the table 34 turns back to its receiving position when the fingers are back at the end of the stroke and 30 that while a plate is being delivered to the table 34 the plate preceding it is being shaved so that the machine will operate on a plurality of plates at the same time.

It will be seen that with this construction 35 the plate can be carried along in substantially a straight path and trimmed on all four edges and shaved on the back without diverting it from its course. In this way, a narrow machine can be used and yet the 40 length of the same is not proportionately increased. It is to be observed, also, that very simple and effective mechanism is shown for accomplishing the several results specified and that the order of the different steps is such that the plates can be effectively operated upon and a plate can be delivered into one end of the machine before the preceding plate has been discharged from the other.

50 While I have illustrated and described two preferred embodiments of the invention, I am aware that many modifications can be made therein by any person skilled in the art without departing from the scope 55 of the invention as expressed in the claims. Therefore, I do not wish to be limited to all the details of construction herein shown and described, but

What I do claim is:—

60 1. In a machine of the character described, the combination with means for moving stereotype printing plates, of two sets of trimming cutters arranged substantially in alinement with each other and with the moving means, and means for feeding

the plates substantially in a straight line from the moving means to the two sets of trimming cutters and presenting different edges of the plates to the two sets of cutters.

70

2. In a machine of the character described, the combination, of two sets of trimming cutters arranged substantially in alinement with each other and with a plate support, a shaving device between the two sets of trimming cutters, and means for feeding the plates substantially in a straight line to the two sets of trimming cutters.

75

3. In a machine of the character described, the combination with a plate support, of a trimming device, a shaving device arranged between the plate support and the trimming device, and means for feeding plates in substantially a straight line, 80 through the shaving device to the trimming device.

85

4. In a machine of the character described, the combination of means for feeding cast plates substantially in a straight line, means for trimming two edges of the plates, and means for thereafter trimming the other two edges while they travel along.

90

5. In a machine of the character described, the combination of means for moving cast plates, means for trimming two opposite edges of the plates, means for giving each plate substantially a quarter turn, and means for thereafter trimming the other two edges.

95

6. In a machine of the character described, the combination of means for taking stereotype printing plates and conveying them along substantially in a straight line, means for giving each plate substantially a quarter turn, and means for performing a finishing operation on the plate both before and after it receives its quarter turn.

100

7. In a machine of the character described, the combination of means for conveying plates along, means for turning the plates, means for trimming two edges of each plate before they are turned, and means for trimming the other two edges after they are turned.

105

8. In a machine of the character described, the combination of means for removing the plates from a plate support and for conveying them along a path in the same general direction, means for trimming the plates, means for turning the plates, finishing means located between the support and the turning means, and finishing means located on the opposite side of the turning means, and in alinement with the other finishing means and the plate support.

110

9. In a machine of the character described, the combination of means for removing the plates from a plate support and for conveying them along a path in the same

115

general direction, means for turning the plates, finishing means located between the support and the turning means, and a finishing device located beyond the turning means 5 and movable transversely to the path of travel of the plates.

10. In a machine of the character described, the combination of means for conveying the plates along a path, means for 10 giving the plates substantially a quarter turn, a finishing device located beyond the turning means, and means for moving the finishing device transversely to the path of travel of the plates.

15. 11. The combination of a carrier for moving stereotype printing plates, trimming saws arranged in position to trim the edges of the plates as they are moved along by said carrier, means for turning each plate 20 substantially a quarter after it passes said trimming saws, and additional trimming saws arranged substantially in alinement with the first ones for trimming the other edges of the plate after it has been turned.

25. 12. In a machine of the character described, the combination of a carrier for moving a stereotype printing plate along a path, a finishing device in position to operate on the plate while being moved by 30 the carrier, a table in position for receiving the plate from the carrier, and means for turning the table substantially a quarter revolution.

35. 13. In a machine of the character described, the combination of a carrier for moving a stereotype printing plate along a path, a finishing device in position to operate on the plate while being moved by the carrier, a table in position for receiving 40 the plate from the carrier, means for turning the plate, and a second carrier for advancing the plate in the same direction from the table.

45. 14. In a stereotype plate finishing machine, the combination of a carrier for the plate, means for moving the carrier, means for trimming two edges of each plate during the motion thereof, a table for receiving the plate from the carrier, means for releasing the carrier from the plate when the plate rests on the table, means for giving the table substantially a quarter turn, means for thereafter moving the plate from the table in the same general direction, and means for trimming the other two edges 55 of the plate after it is removed from the table.

60. 15. In a stereotype plate finishing machine, the combination of a carrier for the plates, means for moving the carrier, means for trimming two edges of each plate during the motion thereof, a table for receiving the plate from the carrier, means for releasing the carrier from the plate when the plate rests on the table, means for giving 65

the table substantially a quarter turn, and means for thereafter finishing the back of the plate.

16. In a stereotype plate finishing machine, the combination of a carrier for the 70 plate, means for moving the carrier longitudinally, means for releasing the carrier from the plate, means for thereafter giving the plate substantially a quarter turn, and a second carrier for carrying the plate forward 75 in the direction in which it was moved by the first carrier.

17. In a stereotype plate finishing machine, the combination of a carrier for a plate, means for reciprocating said carrier, 80 means for releasing the carrier from the plate near one end of its stroke, and a second reciprocating carrier movable independently of the first carrier for moving the plate forward in the same direction after 85 it is released from the first carrier.

18. In a stereotype plate finishing machine, the combination of three supports for a flat plate, reciprocatory means for moving the plate on the first support, reciprocatory means for moving the plate from the first support to the second in the same direction and for moving it on the third support, and means for giving the first support substantially a quarter turn while the plate 95 is on it.

19. In a stereotype printing plate finishing machine, the combination of three supports for printing plates arranged in alinement, means for moving a plate successively 100 from the first support to the second and from the second to the third, and means for giving one of said supports substantially a quarter turn while the plate is on it.

20. In a stereotype printing plate finishing machine, the combination of three supports for cast plates arranged in alinement, means for moving a plate successively from the first support to the second and from the second to the third, means for giving one of 110 said supports substantially a quarter turn while the plate is on it, means for finishing two edges of the plate before it is given its quarter turn, and means for finishing the other two edges after it is given the quarter 115 turn.

21. In a machine for finishing stereotype printing plates, the combination of a reciprocatory member, a carrier pivotally mounted thereon and having a hook for engaging 120 a plate, a support on which said carrier is adapted to carry the plate, and means for swinging the hooks to release the same from the plate when the plate is on the support.

22. In a machine for finishing stereotype 125 printing plates, the combination of a reciprocatory member, a carrier pivotally mounted thereon and having a hook for engaging a plate, a support on which said carrier is adapted to carry the plate, and vertically 130

- reciprocating means for swinging the hook to release the same from the plate when the plate is on the support.
23. In a machine for finishing stereotype printing plates, the combination of a reciprocatory member, arms mounted thereon, hooks pivoted on said arms and adapted to engage a printing plate, springs for holding the hooks up in position to carry the printing plate as the member reciprocates, said hooks having a projection, and means for moving said projection to lower said hooks and disengage them from the plate.
24. In a machine for finishing stereotype printing plates, the combination of a reciprocatory member, hooks carried thereby and adapted to engage a printing plate, means for holding the hooks up in position to carry the printing plate as the member reciprocates, said hooks having a projection, means for raising said projection before the member moves to the limit of its stroke, whereby said hooks will be lowered and disengaged from the plate, and a table for receiving the plate.
25. In a machine for finishing stereotype printing plates, the combination of a reciprocatory member, hooks carried thereby and adapted to engage a printing plate, means for holding the hooks up in position to carry the printing plate as the member reciprocates, said hooks having a projection, stationary guides, a vertically reciprocable member, means for raising the reciprocatory member to engage and lift said projection.
26. In a machine for finishing stereotype printing plates, the combination of a reciprocatory member, hooks carried thereby and adapted to engage a printing plate, means for normally holding the hooks up in position to engage the printing plate, said hooks having a projection, a vertically reciprocatory member, a rod carried thereby for moving said projection and resilient means for moving the rod toward said hooks.
27. In a machine for finishing stereotype printing plates, the combination with a horizontally reciprocable plate carrier, having a swinging member for engaging the plates, of a vertically reciprocable member, a rod resting on the last named member and movable horizontally therealong, and adapted to engage the swinging member to operate it, and yielding means for normally drawing the rod horizontally toward the swinging member.
28. In a machine for finishing stereotype printing plates, the combination with a reciprocable plate carrier, means movable transversely to the direction of motion thereof for disengaging it from a plate, and yielding means for moving said transversely movable means along with the plate carrier during a part of its stroke.
29. In a stereotype printing plate finishing machine, the combination of an oscillatable table for supporting a printing plate, a shaver table, a support between said tables, means for oscillating the first named table, and means for thereafter moving a plate therefrom, over the support, to the shaver table.
30. In a stereotype printing plate finishing machine, the combination of an oscillatable table for supporting a printing plate, a shaver table, means for oscillating the first named table, means for thereafter moving a plate therefrom to the shaver table, and a shaver reciprocable over the shaver table transversely to the direction of motion of the plate.
31. In a stereotype printing plate finishing machine, the combination of a shaver table, means for moving a plate thereon, a slide reciprocable over said table transversely to the direction of motion of the plate, and a shaver mounted on the slide.
32. In a stereotype printing plate finishing machine, the combination of a shaver table, means for moving a plate thereon, a slide reciprocable over said table transversely to the direction of motion of the plate, a rotary shaver on the slide and means for rotating the shaver while the slide travels.
33. In a stereotype printing plate finishing machine the combination of a shaver table, means for moving a plate thereon, a slide reciprocable over said table transversely to the direction of motion of the plate, a shaft journaled on the slide, a rotary shaver and a pulley on said shaft, an idler movable with the slide and at a distance from the shaft greater than the extent of travel of the slide, two idlers turning on stationary axes between the first named idler and the pulley, and a belt over said pulley and idlers.
34. In a machine of the character described, the combination with means for supporting stereotype printing plates, of two sets of cutters, and means for feeding the plates substantially in a straight line from the supporting means to the two sets of cutters.
35. In a machine of the character described, the combination with means for supporting stereotype printing plates, of means for feeding the plates therefrom substantially in a straight line, means for trimming two edges of the plates, and means located in fixed position for thereafter trimming the other two edges.
36. In a machine of the character described, the combination with a support for stereotype plates, of means for removing the plates from the support, means for trimming two opposite edges of the plates, means for giving each plate substantially a quar-

ter turn, and means for thiereafter trimming the other two edges.

37. In a machine of the character described, the combination of a support for stereotype printing plates, of means for taking the plates from the support and conveying them along substantially in a straight line, means for giving each plate substantially a quarter turn, and means for performing a finishing operation on the plate both before and after it receives its quarter turn.

38. In a machine of the character described, the combination of means for con-

veying plates along in a single general direction, means for turning the plates, means for trimming two edges of each plate before they are turned, and means for trimming the other two edges after they are turned.

In testimony whereof I have hereunto set my hand, in the presence of two subscribing witnesses.

HENRY A. WISE WOOD.
